UNITED STATES PATENT OFFICE.

HARRY WATSON, OF BRANDON, MISSISSIPPI.

SELF-SETTING CLOCK.

998,819.

Specification of Letters Patent. Patented July 25, 1911.

Application filed April 17, 1911. Serial No. 621,526.

To all whom it may concern:

Be it known that I, HARRY WATSON, a citizen of the United States, residing at Brandon, in the county of Rankin and State 5 of Mississippi, have invented a new and useful Self-Setting Clock, of which the following is a specification.

This invention relates to self-setting clocks.

10 The object of the invention is to provide novel means whereby the striking train of a clock movement will be automatically adjusted to proper relation to the time train when for any reason such relation has been 15 disturbed, and to secure this result without requiring any extended or expensive changes in clock movements already in use.

It frequently happens when a clock has run down, or has stopped from any cause, 20 that in resetting, the relation of the time train to the striking train is disturbed, so that consonance between the two trains is temporarily destroyed, and the number of strokes given on the bell or other alarm will 25 thus not agree to the time indications on the clock.

In the present invention provision is made whereby the two trains will be brought into proper relation by the progressive movement 30 of the time train without any attention on the part of the person winding or setting the clock, this result being secured every twelve hours, the self-setting mechanism being otherwise inactive.

35 With the above and other objects in view, as will appear as the nature of the invention is better understood, the same consists in the novel construction and combination of parts of a self-setting attachment for clocks, as 40 will be hereinafter fully described and claimed.

In the accompanying drawing forming a part of this specification, and in which like characters of reference indicate corresponding parts: Figure 1 is a view in side elevation of a portion of a clock movement, showing the improvements of the present invention applied thereto, a part of the plate or frame of the clock being broken away for 45 clearness of illustration. Fig. 2 is a view in side elevation of a pawl that coacts with the hour wheel, locking wheel, and count wheel to secure the proper setting of the striking train relative to the time train. 50 Fig. 3 is a view taken from one edge of the pawl. Fig. 4 is a similar view taken from

the other edge. Fig. 5 is a vertical transverse sectional view taken on the line 5—5 Fig. 1, and looking in the direction of the arrow thereon.

60 Referring to the drawings, 1 designates generally the front plate of a clock frame, such as is commonly employed in time and striking trains, especially of the eight-day type, and as the present invention has to do 65 only with the hour wheel, count wheel, and locking wire, all the other parts have been omitted.

65 Of the parts illustrated 2 designates the hand arbor, 3 the hour wheel, 4 the count 70 wheel, 5 the count wheel arbor, 6 the locking wire, and 7 the arbor of the locking wire. The count wheel 4 is modified only in so far as being the provision of an outwardly projecting pin 8 for a purpose that will pres- 75 ently appear.

75 Mounted upon the hour wheel 3 or upon a sleeve surrounding the arbor 2 and made fast to the wheel or arbor, is a disk 9 provided at one point with a notch 10 leading 80 from the periphery toward the axis of the disk, the notch being of wedge shape, or of any other appropriate form, which will answer the function presently to be described.

85 Pivoted to the frame is a pawl or arm 11 which forms one of the essential features of the present invention, and which is shown in detail in Fig. 2. The pawl at the end remote from its pivot 12 is formed with a 90 tooth 13 arranged to engage with the notch 10 of the disk 9, and at a point about midway of its length is provided with a cam face extension 14 that is arranged in the path of movement of the pin 8.

95 The locking wire 6 is similar to the type ordinarily employed in striking movements except that it is provided with a shoulder or offset 15 designed to be engaged by a finger or detent 16 upstanding from the pawl at 100 its pivotal point, the finger being of such length that when the tooth 13 is in the notch 10, the locking wire will be held out of contact with the count wheel. The tooth 13 is so related to the notch 10 in the disk 9, and the latter so related to the hour wheel 3 that once in every revolution of the latter, the tooth 13 will drop into the notch if not prevented, and during the remainder of the 105 revolution of the wheel 3, the point of the tooth will ride on the periphery of the 110 disk 7.

The parts are so related that when the pawl 11 has its tooth lodged within the notch of the disk, the finger 16 will under-
 ride the shoulder or projection 15 of the
 5 locking wire, and the latter will be main-
 tained in elevated position with its end out
 of engagement with the notches of the count
 wheel, even though in the ordinary opera-
 10 tion of the striking train it would fall into
 some of these notches. The result of this is
 that the count wheel will continue its rota-
 tion and cause the progressive action of the
 striking train so long as the wire 6 is main-
 15 tained in its elevated position. Ultimately,
 however, in the rotation of the count wheel,
 the pin 8 is brought into contact with the
 cam face extension 14, and the pawl 11 is
 moved about its pivot until the tooth 13 is
 20 moved from the notch 8 when the finger 16,
 moving in an arc about the pivot point of
 the pawl 11, will escape from beneath the
 shoulder 15 and so release the locking wire
 and permit it to drop into locked engage-
 25 ment with the count wheel and thereby ar-
 rest its further movement. The notch 10 is
 of such size and is so located that it has been
 moved out of the path of the tooth 13 by the
 progressive movement of the time train
 30 before the striking train is again released,
 and consequently the tooth 13 will remain
 on the periphery of the disk 9 so that the
 finger 16 is held out of the path of the lock-
 ing wire.

When the time and striking trains of the
 35 clock are in proper relation, the pin 8 will
 always engage the cam face extension 14
 whenever the notch 10 is coincident with the
 tooth 13, thus preventing it from dropping
 into the notch. The pawl 11 is then inert
 40 relative to the locking wire, so long as the
 proper relation is maintained between the
 two trains of the clock. Suppose, however,
 that the coöperative relation of the two
 45 trains of a clock should be out of conso-
 nance, either by reason of the clock running
 down and of having been rewound or reset
 without attention to the striking train, or of
 the clock hands having been moved to such
 50 an extent as to cause the two trains of the
 clock to be out of harmony, and the striking
 train no longer agrees with the time train.
 Then when the notch 10 moves into coinci-
 dence with the tooth 13, the pin 8 is no
 55 longer in such relation to the pawl as to
 elevate it and therefore the tooth 13 will
 drop into the notch 10 just as the locking
 wire is being elevated to release the count
 wheel, the parts being so adjusted as to
 60 cause this order of action. Now when the
 locking wire 10 is to move downward to a
 sufficient extent to cause its free end to enter
 a notch in the count wheel, it is caught by
 the finger 16 and is prevented from enter-
 65 ing the notch and thus stops the striking
 train, which then continues until the pin is

brought against the cam extension 14, and
 the pawl is elevated to carry the tooth 13 out
 of the notch 10 and the finger 16 from be-
 70 neath the shoulder 15, so that the locking
 wire may now drop into a count wheel notch,
 thus arresting the further operation of the
 striking train. The parts are so proportioned
 75 that the striking train and the time train
 are now in proper relation, and this is main-
 tained until again disturbed by some cause
 other than the normal operation of the clock
 movement. Whenever the proper relation
 80 of the time and striking trains is disturbed,
 it is again automatically reestablished within
 a twelve hour movement of the hour wheel
 3 at the longest, but usually this relation is
 established in much less time.

It will be understood that the showing of
 the drawing is more or less diagrammatic
 and is not intended to show any exact rela-
 85 tion which will vary with different clock
 movements.

I claim:

1. In a combined time and striking clock,
 a count wheel, a locking wire, a detent for
 90 the wire, and means controlled by the time
 train when out of proper relation to the
 striking train to cause the detent to hold
 the locking wire inactive relative to the
 95 count wheel until the proper relation of the
 two trains is established.

2. In a combined time and striking clock,
 a count wheel, a locking wire, a detent mov-
 100 able into and out of operative relation to
 the locking wire, and means controlled by
 the time train and coacting with the de-
 tent to maintain the latter inactive relative
 to the locking wire except at predetermined
 105 points in the movement of the time train.

3. In a combined time and striking clock,
 a count wheel, a locking wire, a detent mov-
 110 able into and out of operative relation to
 the wire, means controlled by the time train
 to cause the movement of the detent into op-
 erative relation to the locking wire, and
 means controlled by the striking train to
 115 render the detent inactive at all times while
 the time and striking trains are in proper
 relation.

4. In a combined time and striking clock,
 a count wheel, a locking wire, a detent mov-
 120 able into and out of operative relation to
 the locking wire, a pawl carrying a detent
 movable into and out of operative relation
 to the wire and provided with a tooth and
 with a cam face extension, a projection on
 the count wheel arranged to engage the cam
 extension, and a disk on the hour wheel
 with its periphery in the path of the tooth
 and provided with a notch to receive the
 125 same.

5. In a combined time and striking clock,
 a count wheel, a locking wire having a shoul-
 130 der, a pivoted pawl provided with a finger
 arranged to engage the shoulder, and fur-

nished further with a tooth and with a cam faced extension, a projection on the count wheel to engage the extension, and a disk on the hour wheel with its periphery in the path of the tooth and having a notch to receive the same.

In testimony that I claim the foregoing

as my own, I have hereto affixed my signature in the presence of two witnesses.

HARRY WATSON.
